United States Patent Office

Des. 227,755
Patented July 17, 1973

227,755

TELEPHONE KIOSK

Gerald J. Adamson, Scarborough, Ontario, and Jan W. Kuypers and Ian F. Norton, Toronto, Ontario, Canada, assignors to Don Mills Development Limited, Toronto, Ontario, Canada

Filed Nov. 11, 1971, Ser. No. 198,091

Term of patent 14 years

Int. Cl. D25—99

U.S. Cl. D13—1 L

FIG. 1

FIG. 2

FIG. 1 is a perspective view taken from the front to one side of a telephone kiosk embodying our new design, and

FIG. 2 is a perspective view from the rear to the opposite side thereof.

The bottom of said telephone kiosk is plain.

We claim:

The ornamental design for a telephone kiosk, as shown and described.
